UNITED STATES PATENT OFFICE.

JOHN H. GARRITY, OF PITTSBURGH, PENNSYLVANIA.

DESIGN FOR A GRACE-PRAYER HOLDER.

47,133.

Specification for Design.

Patented Mar. 23, 1915.

Application filed July 10, 1914. Serial No. 850,263. Term of patent 7 years.

To all whom it may concern:

Be it known that I, JOHN H. GARRITY, a citizen of the United States, residing at North Side, Pittsburgh, in the county of Allegheny and State of Pennsylvania, have invented a new, original, and ornamental Design for Grace-Prayer Holders, of which the following is a specification, reference being had to the accompanying drawings, forming part thereof.

The figure is a front elevation of a grace prayer book illustrating my new design.

The design is formed of a unitary body, either metal, glass, or china ware and which has the appearance of an open book resting upon an easel or book support. The open book has printed, or otherwise thereon, a prayer of grace.

I claim—

The ornamental design for grace prayer holder as shown and described.

JOHN H. GARRITY.
